UNITED STATES PATENT OFFICE.

WILLIAM H. ROSE, OF JERSEY CITY, NEW JERSEY.

WIND DEFLECTOR.

Application filed April 13, 1927. Serial No. 183,590.

My invention relates to wind deflectors and refers particularly to devices of this character adapted to be positioned within a window frame and to deflect the air passing 5 inwardly through an open window.

Among the objects of my invention is a device of the character described which is strong and light in weight, economic in construction, which can be packed and shipped 10 in flat condition and which can be readily introduced into and removed from its operative position.

Corrugated cardboard is a most desirable material for the production of wind deflec- 15 tors, as it is cheap, can be shipped in flat form and easily bent into the desired shape, is light and can be made water proof by means of paint or varnish.

Corrugated cardboard, however, is not 20 practical for the purposes indicated as wind deflectors must be attached to window frames, preferably by means of nails, or screws. The formation of corrugated cardboard is of such character, that the heads of 25 the fastening means are forced inwardly of the cardboard in attaching the latter to a window frame, thus preventing a tight jointure.

Another undesirable feature of corrugated cardboard for this purpose is that the cardboard is liable to tear away from the fastening means, any pressure or strain having a tendency to pull the nail, or screw, through the cardboard, thus destroying the 35 usefulness of the device.

My invention allows the use of corrugated cardboard for wind deflectors as it overcomes the objectionable properties above described and completely prevents the entry of the 40 heads of the nails, or screws from entering the cardboard, thus allowing firm connections between the device and the window frame and also completely overcoming the possibility of a cardboard tearing away 45 from the fastening means because of strains, or stress, brought to bear upon the device.

My device comprises a corrugated card- 50 board wind deflector, the fastening portions of which carry a metallic strengthening member, or strip, having holes therein through which the fastening means may be inserted. The inner edge of the strengthen- 55 ing means carries a plurality of teeth inserted within the cardboard. Any strain, therefore, upon the device is not brought to

bear simply upon the nails, or screws, used for fastening purposes, thus tending to tear the fastening means through the cardboard, but such strain is supported by the plurality of teeth and hence distributed over the entire metal strengthening member. 60

It will thus be seen that my device overcomes the inherent weakness of the corrugated cardboard and presents a device of great value and usefulness. 65

In the accompanying drawings illustrating modified forms of the device of my invention, similar parts are designated by similar numerals.

Figure 1 is a perspective view of one form 70 of my device mounted within a window frame.

Figure 2 is a cross-section through the line 2-2 of Figure 1.

Figure 3 is an enlarged vertical cross-section showing a strengthening means and a corrugated cardboard side, the dotted lines indicating the position of the strengthening member before the insertion of its teeth into the cardboard side. 75

Figure 4 is a side view of the strengthening means.

Figure 5 is an end view of Figure 4.

Figure 6 is a top view of Figure 5.

Figure 7 is a broken side view of a modified form of strengthening member. 80

The particular form of the device of my invention shown in the accompanying drawings comprises a blank of corrugated cardboard scored and bent along the lines A-A and B-B, thus forming the front member 10, and the two triangular side members 11 and 12.

A metal strengthening member 13 of U shaped construction, having the inwardly ex- 85 tended staggered teeth 14, 14 is placed around the upright edge of each side mem- ber 11 and 12 and the teeth 14, 14 pressed in- wardly into the corrugated cardboard of which each side member is composed. 100

The two series of teeth 14, 14 in addition to being staggered with respect to each other are offset with respect to each other by making one side of the member 13 slightly longer than the other side. These staggered and off-set positions of the teeth are desirable as they preserve the strength of the corrugated cardboard, which would otherwise be weakened by the inserted teeth. 105

Each strengthening member 13 has a plu- 110
